INVENTOR

Arthur H. Parsons.

By Fisher & M. A. M.

UNITED STATES PATENT OFFICE.

ARTHUR H. PARSONS, OF CLEVELAND, OHIO, ASSIGNOR TO THE PARSONS & PARSONS COMPANY, OF CLEVELAND, OHIO, A CORPORATION OF OHIO.

COLLAR.

1,056,443.

Specification of Letters Patent.

Patented Mar. 18, 1913.

Application filed June 22, 1908. Serial No. 439,753.

To all whom it may concern:

Be it known that I, ARTHUR H. PARSONS, a citizen of the United States, residing at Cleveland, in the county of Cuyahoga and State of Ohio, have invented certain new and useful Improvements in Collars, and do declare that the following is a full, clear, and exact description of the invention, which will enable others skilled in the art to which 10 it appertains to make and use the same.

My invention relates to improvements in collars for neck wear, and the improvement consists in a collar constructed substantially as hereinafter shown and described and more particularly pointed out in the claims.

In the main, the object is to produce a serviceable collar, one which will stand hard usage and have long life.

A large part of the strain to which a collar is put is at the time of buttoning and unbuttoning the same, and in so doing the collar and its buttonhole members are twisted and pulled to the detriment of the collar especially at the top fold immediately at the 25 meeting front edges of the collar. Tearing or cracking of the collar from this point along the fold line is sure to occur in a short time, and this is the chief objection in rubber or celluloid collars to which this improvement particularly applies, although not necessarily confined to this class of collars. Then again, as the material referred to makes a stiff collar which does not readily flex or bend, comparatively speaking, the 30 wearer has difficulty in putting the collar on, both at the front and back.

My improvement facilitates the buttoning and unbuttoning of the collar both front and back, because the buttonhole members 40 are particularly constructed to give perfect freedom of operations and a maximum of flexibility at the points most needed and with a view of preventing tearing and cracking of the collar as aforesaid.

In the accompanying drawings, Figure 1 is a perspective view of my improved collar viewed from the front. Fig. 2 is a sectional view in plan of a portion of a collar and illustrating more particularly the free relation of a buttonhole member to the front edges where overlapping occurs. Fig. 3 is a perspective view of the collar shown in Fig. 1 but viewed from the side. Fig. 4 is a sectional detail and inside face view of a portion 50 of a collar somewhat modified from the

former views, but illustrative of the button-hole tab or extension member as it appears when first cut and before being bent upward to lie and bear against the body portion of the collar which comes against the neck of 60 the wearer when in use.

The collar —2— shown, is of the lay-down variety, having an inner wall or neck engaging portion 3 and an outer wall or turn down portion 4. However, the exact 65 form of collar here shown need not be followed as the invention is not limited to any particular style of collar, and may even be used to advantage with so-called stand up collars, especially of the kind having wings 70 or folds at their front ends. In the present instance, inner wall 3 is slit or cut on line 5 oppositely on the collar and from front edge 6 back to a rounded opening —7— at the rear of the collar and at each side of the rear 75 buttonhole tab 8. This tab is formed out of the inner stock or wall 3 by cutting V shaped notches 9 at each side of buttonhole 10 and relatively to a height approximately as shown in the drawings, although the 80 depth of the cut may be even greater to provide a more flexible and free tab 8. The tab shown gives perfect freedom to the fingers when buttoning the collar upon the shirt as it will flex inward sufficiently to permit the 85 fingers to come between the outer and inner walls or folds and do their work, thus facilitating putting on the collar without undue strain to the parts and without hampering or inconveniencing the operator. 90

Now, attention is directed to the relation of openings 7 to notches 9 and tab 8, whereby an upwardly curved neck or inner end portion 11 is provided for the strips 12 which form the front buttonhole members 95 14 and 15, respectively, and which strip and members are therefore integral parts of the collar and of the same piece thereof. The buttonhole member or extensions 14 and 15 are designed to have such width or depth 100 at their overlapping ends that full and sufficient engagement may be had with the neck band of the shirt and that the buttonholes 16 therein will coincide and bring the meeting edges 6 in close proximity and in 105 alinement with each other, especially at the top fold line. Therefore, the greater amount of stock taken up from the inner wall 3 is used in making said buttonhole members but only at the front thereof, and to this 110

2

end slot or cut 5 runs downward at an inclination to the top fold or edge of the collar from the front to the rear where it is purposely designed to narrow the strips 12 and 5 then by curving the slot upward to provide neck 11. The object in so doing is two-fold; first, to provide the requisite backing for the buttonhole members at the immediate front end of the collar by forming a down 10 flange or wall portion 17 with edges —6—, and second, to provide the necessary elasticity and give at the connecting end of the strip 12 by forming neck 11 and whereby said strip and especially the front buttonhole extension thereof may be carried upward between walls 3 and 4 and lie flush upon the wall 3 and be supported thereby. The upper edge 18 of the buttonhole members 14 and 15 is brought very close to the 15 rounded fold line of the collar, for appearances primarily, but also to get a sufficient backing for the said members so that the front of the collar will fit the neck band and neck of the wearer and conform to the 20 curves or lines thereof. The members 14 and 15 when raised are permanently secured in this position by cement, preferably, the stippled portion indicated by 19 on Fig. 4 showing the relative area covered by the 25 cement.

It is quite essential to have a fixed attachment of the strip 12 to the collar body other than the integral connection by neck 11 and especially at or near the free or buttonhole 30 end, and this is obtained by the cement union referred to. However, any other fastening means may be used in place thereof, or may supplement the same if desired. Now as to this union, it will be especially noted that 35 a portion of the overlapping parts are left free from each other some distance back

from edge 6 and extending to the edge. This may be even more than shown, and its purpose is to provide perfect freedom for the manipulation of the button-hole ends, 45 and also and the more important, to prevent abrasion, wear, and strain upon the collar at the fold corner at edge 6.

In the making of the various styles of collars called for by the trade and public, 50 the lines of the tabs or button-hole extensions would be variously modified to meet different conditions, and this is especially true of the bottom line of the tabs which rest upon and against the shirt, and depending whether either a high or low collar is wanted. But this will not affect the salient and material features of the invention, and therefore, no limitations as to such details is intended. 55

60 What I claim is:—

1. A collar having buttonhole tabs severed from the lower portion thereof inward from its ends and integral therewith and having a rounded opening at the inner ends of said 55 lines of severance, and said tabs overlapped along their cut edges and lying in approximately their original relation to the collar from end to end.

2. A collar and integral tabs thereon severed therefrom along their upper edges from the front transverse edges of the collar to their inner ends, and said tabs raised in respect to said line of severance but otherwise sustaining their original relation to the 75 collar.

In testimony whereof I sign this specification in the presence of two witnesses.

ARTHUR H. PARSONS.
